UNITED STATES PATENT OFFICE.

MOTTEL CLAR, OF FORT MORGAN, COLORADO.

RADIATOR.

1,316,425.

Specification of Letters Patent. Patented Sept. 16, 1919.

Application filed August 28, 1918. Serial No. 251,813.

To all whom it may concern:

Be it known that I, MOTTEL CLAR, a citizen of the United States, residing at Fort Morgan, in the county of Morgan and State of Colorado, have invented new and useful Improvements in Radiators, of which the following is a specification.

This invention relates to radiators, for motor vehicles, particularly to those of the tube type, and has for its object the provision of a radiator substantially all of the component parts of which are held in assembled relation by means of a plurality of stay rods, removal of which permits disassembling of all the different parts of the radiator whereby access may be readily had when repairs are necessary.

An important object is the provision of a radiator of this character which is so constructed that the tubes are disposed in clamped relation between the upper and lower tanks of the radiator without the use of solder or other securing means other than the stay bolts employed for holding the upper and lower tanks in assembled relation.

A further object is the provision of a radiator of this character in which the radiating fins as well as the tubes may be quickly and easily removed and whereby the radiating fins may be removed without disturbing the position of the tubes.

Another object is the provision of a radiator of this character which will be simple and inexpensive in manufacture, easily assembled and disassembled, highly efficient and durable in use, which will require but little labor for repairing, and which will be a general improvement of the art.

With the above and other objects and advantages in view, the invention consists in the details of construction to be hereinafter more fully described and claimed and illustrated in the accompanying drawings in which:—

Figure 1 is a front elevation of the radiator entirely assembled.

Fig. 2 is a similar view of the radiator proper with the outer incasing shell shown in section and with the radiating fins removed.

Fig. 3 is a cross sectional view on the line 3—3 of Fig. 1.

Fig. 4 is a side elevation of the radiator proper with the outer shell removed.

Fig. 5 is a detail view of the upper tank

illustrating the connection of the overflow pipe, the tank being shown in section.

Fig. 6 is a detail cross sectional view through the lower tank.

Fig. 7 is a bottom plan view of the lower tank.

Fig. 8 is a bottom plan view of the radiator supporting plate.

Referring more particularly to the drawing, the numeral 10 designates the outer shell of the radiator which may be of any desired contour and which is designed to serve as a protection for the radiator proper which is designated by the numeral 11. The radiator proper 11 is shown as comprising upper and lower tanks 12 and 13 respectively between which extend and with which communicate the vertically disposed spaced tubes 14. This arrangement of parts is old and well known and no novelty is claimed for the general arrangement.

In carrying out my invention I form the upper tank 12 of two sections or pans, the lower one 15 being formed preferably as a casting and having an open top in which is telescopically received the upper pan 16 which is soldered in place at its line of juncture with the lower pan. The upper pan 16 is provided with the usual filling neck 17 which extends through the shell 10 in the usual manner. Throughout its periphery, the lower pan 15 of the upper tank 12 has formed thereon a plurality of spaced lugs 18 which are apertured as shown for a purpose to be described. Extending downwardly from the bottom of the lower pan 15 and cast integrally therewith, is a plurality of nipples 19 within which are reduced extensions, 20, these members being provided with a bore 20^a communicating with the interior of the upper tank.

The lower tank 13 is very similar in construction to the upper tank 12 and is formed in two sections, an upper pan 21 which is formed preferably of cast metal and a lower pan 22 which is telescoped into the pan 21 and soldered thereto at its line of juncture therewith. The upper pan 21 of the lower tank has cast thereon a plurality of upwardly extending nipples 23 within which are reduced extensions 24 provided with bores 25 communicating with the interior of the lower tank. This pan 21 has cast thereon throughout its periphery a plurality of lugs 26 which are apertured for the recep-

tion of vertically disposed stay rods 27 which extend also through the apertured lugs 18 and which are provided with clamping nuts 28.

5 The water tubes 14 are of ordinary construction and are formed preferably of copper and have their ends outwardly flared as shown to provide flanges 29 which are adapted to be disposed within the space between each nipple 19 and its reduced portion 20. This space between each nipple 19 and its extension 20 is partially packed with any suitable packing material 30 which is engaged by the flanges 29 so that a tight joint may be formed.

10 The radiator is assembled by placing the tubes 14 in position upon the lower tank 13 with the flanged lower ends of the tubes disposed within the spaces between the nipples 23 and the extensions 24 and with the extensions 24 entering the tubes. The upper tank 12 is then placed upon the upper end of the tubes 14 with the nipple extensions 20 disposed within the upper ends of the tube and 15 the tube flanges disposed within the spaces between the nipples 19 and the extensions 20. The stay rods 27 are then inserted through the alined lugs 18 and 26 and the nuts 28 are applied to the threaded ends of 20 the stay rods and screwed firmly into place so that the upper and lower tanks 12 and 13 will be drawn together into clamping relation with the ends of the tubes 14. The provision of the packing at the ends of the tubes 14 insures the formation of water 25 tight joints so that all possibility of leaks will be prevented.

30 The lower pan 15 of the upper tank is of course provided with a pipe 31 and the upper pan of the lower tank is provided with a pipe 32, both of these pipes being of ordinary construction and affording means whereby the radiator may be connected in the water circulatory system of the motor. 35 The pipe 32 is provided with the usual drain cock 33 so that the radiator may be drained when necessary.

35 In order to reinforce the lower tank so that any possible buckling thereof will be prevented, I provide a supporting plate 34 disposed against the bottom of the lower tank and provided with a depressed portion 35 for the accommodation of the pipe 32, this depressed portion 35 being provided 40 with a recess 36 for the accommodation of the drain cock 33. This plate 34 is of greater width than the bottom tank 13 for a purpose which will be hereinafter made apparent, and has its end portion provided 45 with holes 37 for passage of the usual threaded studs, not shown, for securing the assembled radiator in place upon a chassis.

50 At a convenient point in its length, the lower pan 15 of the upper tank is provided 55 with a downwardly extended nipple 38 into

the bore of which is threaded the lower end of an overflow tube 39 disposed within the upper tank and having its upper end terminating within the filling neck 17 in the usual manner. The portion of the overflow pipe 70 which is disposed exteriorly of the tank is designated by the numeral 40 and has its upper end flanged for engagement within a union 41 threaded upon the nipple 38 whereby the tube 40 may have communication with 75 the tube 39 while insuring a tight joint at the point of connection.

80 In order to provide radiating surfaces whereby water may be cooled in its passage through the tubes from one tank to the other, I provide two fin carrying sections designated by the numerals 42 and 43 disposed at the front and rear of the body of tubes. Each fin section comprises a pair of spaced uprights 44 which have their lower ends 85 resting upon the portions of the plate 34 extending beyond the sides of the lower tank, as clearly shown in Fig. 4. The fins 45 extend transversely of the tubes 14 and have their ends provided with lugs 46 secured upon the uprights 44 in any desired manner as for instance by means of rivets. The fins carried by the forward section 42 extend rearwardly to the center of the body of tubes 14 and the fins carried by the section 43 extend forwardly and terminate adjacent the center of the body of tubes in slightly spaced relation to the fins carried by the forward section. In order that the fin sections may be quickly applied to or removed from the tubes, instead of providing them with a plurality of circular openings for the passage of the tubes, I provide them with elongated slots 47 for the reception of the tubes.

100 After the body of the radiator is assembled as above described, the fin sections 42 and 43 are applied to the front and rear faces of the body of tubes respectively with the lower ends of the uprights 44 resting upon the side edges of the plates 34. When the outer shell is then applied to the radiator proper, it will engage against the front of the uprights 44 of the section 42 and against the rear of the uprights 44 of the sections 43 so that these fin sections will be held in properly engaging position in respect to the tubes and the other portions of the radiator.

110 From the foregoing description and a study of the drawings it will be apparent that I have thus provided a radiator, the parts of which may be readily and quickly assembled and held in clamped relation so that the use of solder will be avoided, the 115 parts being also capable of ready disassembling so that defective tubes or other parts may be easily replaced in an expeditious manner.

120 While I have shown and described the 130

preferred embodiment of my invention, it will of course be readily understood that I reserve the right to make such changes in the form, construction and arrangement of parts as will not depart from the spirit of the invention nor the scope of the subjoined claim.

What is claimed is:—

A radiator comprising upper and lower tanks, nipples extending from the lower and upper sides of said upper and lower tanks respectively, extensions within said nipples spaced from the walls thereof, said extensions being of greater length than said

nipples and provided with bores communicating with the interior of the tanks, a plurality of tubes disposed between said tanks with their ends telescopically engaging over said extensions, flanges on the ends of said tubes disposed within the spaces between the extensions and the walls of the nipples, resilient packing disposed within said spaces between the bottoms of the nipples and said flanges, and means for holding said tanks in clamping relation with respect to each other. 15 20 25

In testimony whereof I affix my signature.

MOTTEL CLAR.
